HINGE AND STOP PROVISIONS FOR HAND OPERATED IMPLEMENTS OR TOOLS

Claude W. Hart, Seymour, Ind., assignor to Seymour Manufacturing Company, Seymour, Ind., a corporation of Indiana

Application January 7, 1953, Serial No. 330,041

5 Claims. (Cl. 294—50.5)

This invention relates to improvements in hinge and stop provisions for hand operated implements or tools, and more particularly to an improved hinge assembly embodying a novel arrangement of stop elements for use on certain two-handled, bladed hand tools, such as post hole diggers and the like.

For brevity of present description the specification and claims herein are largely directed to a post hole digger of clam or clam shell type, as distinguished from post hole augers, the latter usually having a single rotatable handle with part-helical blades subject to rotary motion for engaging the blades with the earth. Post hole diggers, in distinction, are operated by forcible insertion of a pair of opposed cupped blades into the earth in the location of the hole with handles together, followed by divergence of the handles resulting in convergence of the blades, followed by removal of the earth by direct lifting action of the divergent handles. It is more particularly to the latter type of tools or implements, that the present improvements are directed.

It has heretofore been conventional to construct post hole diggers of a pair of handled blades, and providing the assembly with a yoke structure having bolt apertures, with a pivot pin or bolt extending through such apertures, or alternately, to provide inturned ears on the blades, with bolt holes through the blade ears, a bolt or pin being directed through such apertures as a pivot. Either of these older types is distinctly disadvantageous in that the yoke entails separate expensive elements, and in case the blades themselves carry the pivot bolt apertures, the gauge of metal usually employed in the blades is such as to make for short life of the apertured blade portions, sometimes with a severe cutting action on the pivot bolt, resulting in a considerable wobble or looseness in the pivot region due to wear even after only a short period of service. Furthermore, the need for apertured extensions of the blades solely for purposes of pivoting the companion cooperating parts of the digger, needlessly enhances the cost of cutting and forming tools for production of the blades, and involves a considerable waste of metal of the blade. It is accordingly a principal and major object of the present improvements to reduce the costs of producing the blades of implements of the kind in discussion; to provide a simple, rugged, and much longer lived pivot assembly, with a substantial reduction in cost and a longer useful life of the tool with minimum requirements of service attention thereto.

An additional object of importance consists in the provision of a novel stop arm or arms, located at a distance from the hinge assembly, and embodying a provision for maintaining the handle blades in parallelism between periods of active use or at the end of each working stroke of the tool, at the same time serving to relieve the hinge pin or pivot of twisting or cocking stresses.

Yet another and valuable object of the invention is realized in a hinge assembly for the general purpose noted, which provides an augmented bearing area be-

2

tween the pin and other parts of the hinge proper, thereby reducing unit pressures on the pin when under load.

Of great importance as an objective of the current improvements is the provision of a novel stop and hinge assembly consisting of companion cooperating parts constituting both a hinge structure and a stop or abutment, establishing a limit of inward or convergent movement of the handles, it being noted that the two part stop and hinge assembly is susceptible of usage in a variety of two-handled, usually manually operated, implements or tools.

The foregoing and numerous other objects and advantages of the invention will more clearly appear from the following detailed description of a post hole digger equipped with the present improvements, particularly when the description is considered in connection with the accompanying drawing, in which:

Fig. 1 is a side elevational view of a post hole digger embodying the present improvements;

Fig. 2 is an elevational view taken at a right angle to 20 that of Fig. 1;

Fig. 3 is a view generally similar to Fig. 1, but showing the operative metal parts of a post hole digger together with lower portions of the handles, in section, as viewed along line 3—3 of Fig. 2;

Fig. 4 is a transverse sectional view, partly in elevation, as taken along line 4—4 of Fig. 1, and

Fig. 5 is a transverse sectional view in a plane including the pivot axis, and located by line 5—5 of Fig. 1. In each of Figs. 1—3, the handles are foreshortened somewhat to enable showing the operative metal parts on a somewhat larger scale.

Referring now by characters of reference to the drawing, there is shown by way of illustrative example a post hole digger the general type of which is well known as characterized by a clam shell action, and including a pair of elongate, usually hardwood handles 10 and 11, and a pair of hollow scoop-like blades 12 and 13 respectively attached to the handles 10 and 11, in a manner later to be described. Each of the blades is extended upwardly 40 of the blade body to form an attachment portion or socket, as indicated at 14. In the socket-forming region, the metal of the blades is folded or bent to constitute a pair of parallel flanges 15 and 16 which result in an open-side socket, receiving a squared lower end 17 of the connected handle. Thus the two sockets as assembled to the handles, have their single open sides presented toward each other. Connection of each blade to its operating handle 10 or 11, is made as by a pair or other desired number of assembly bolts 20 extended transversely of the socket and the handle, and provided with external nuts 21 as shown.

Serving as a closure for the open side of each of the handle sockets, is one of a companion pair of members collectively constituting a stop and hinge assembly providing for the operative pivotal connection between the two handled blades of the assembly.

Referring now more particularly to the parts of the stop and hinge structure, it will usually be preferred for reasons of economy, to constitute the companion hinge sections of identical or substantially identical parts, thus conducing to economy in die and tooling costs. In the example shown, each hinge part includes a substantially flat base plate 25. This is shown as provided with squared apertures of a size for the reception of the squared upper shank portion 26 of each of the bolts 20 when the latter are of carriage type. At one, shown as the lower, end of each of the stop-hinge parts, are a pair of ears or projections 27. If the stop-hinge elements are of sufficient gauge or thickness, a single such ear on each part will suffice, but it is preferred for better rigidity and spacing of pivot zones, to provide a pair of such ears 27 in overlapped relation as best shown by Fig. 5, each

3

of the ears 27 being apertured for the reception of a pivot pin exemplified by bolt 30 extending through the apertures therefor, which obviously, in assembly, are all in register. The pivot bolt is provided with a nut 31.

It is greatly preferred for better pivoting action and longer life of the pivot or hinge elements, to utilize metal in the stop-hinge structure, which is of considerably greater weight or gauge than is provided in the blades 12-13. Furthermore, by the provision of stop-hinge elements formed entirely separately from the blades, or independently of the yokes sometimes employed in the pivot region of post hole diggers, a wider choice of materials is possible, as well as certain economies in forming.

The apertured pivot ears 27 of each hinge assembly part, are shown as preferred, at one or the lower end of each of the base plates. Preferably spaced substantially from the pivot ears and at the opposite or uppermost end of the base plate, is a right angle flange turned inwardly of the base plate toward the opposite handle, and indicated at 32, and constituting as will appear, a stop arm serving to limit the extent of approaching movement of the handles toward each other, when opening the blades 12-13 to the maximum extent, prior to loading the blades.

It is a preference so to form and proportion the apertured ears 27 in relation to the stop arms 32 on the companion parts of the hinge and stop assembly, that the effective spacing between the plates 25 realized by the apertured ears 26, is identical with the spacing which results from mutual engagement of the paired stop arms 32. With this relation of parts, when the handles are brought together as closely as possible, with the blades fully open as shown by Fig. 1, the base plates 25 are parallel, as are the handles, with assured spacing therebetween at all times, thus avoiding any possible impact between the handles and the hands of the operator. It will also be noted as desirable to form up the stop arms so that each is at a right angle to the ears 27 of the same fixture.

It will have appeared that the spacing of the stop arms 32 at a substantial distance away from the operative axis of the implement, being in this case the axis of bolt 30, greatly decreases the unit pressures and impact effects on the mating edges of the arms when same are brought together. Such unit pressures are still further minimized by the provision, best appearing in Fig. 4, of a prominent saw-tooth edge on the free margin of each of the stop arms. By reason of this formation there results a series of tongues on the end of each stop arm, and conforming tongue-receiving recesses on the region of the companion stop arm. Thus when so constructed, the tongues such as 33 will interfit corresponding recesses such as 34 of the companion stop arm. In case the pivot bolt should become bent slightly, the interengagement of the tongues and recesses will tend to cam the parts into parallelism when the handles are brought together.

Although the hinge and stop assembly would be similarly operative if only a single stop arm were utilized, the length of which would correspond to the spacing of the plates at their pivoted end with blades open, it is nevertheless preferred to utilize a pair of the arms 32, substantially as shown by Fig. 4 and others.

It will have appeared that when the handles are convergingly actuated and brought as closely as possible together with the stop arms in interfitted relation as shown, this formation of the stop arms, as during periods of haulage, storage or otherwise between periods of usage, maintains the arms in accurate parallelism and relieves the pivot bolt 30 of any cocking or twisting stresses.

A number of advantages result from the utilization of the separate stop-hinge assembly as described, in comparison of this arrangement with older and conventional constructions. In addition to the marked reduction in

blade tooling costs, it enables the use of a much heavier material, as above noted, in the stop and hinge assembly. Similarly, the use of the rigid longitudinal plate 25 as a cover over the otherwise open side of the blade socket, results in substantially a complete embracing relation of the socket to the lower end of the handle, thus tending to obviate wear of the bolts in the bolt passages through the handles, permitting a much tighter takeup of the nuts 21 without drawing the bolts into the wood handles, and likewise providing a rugged, rigid U-shaped bridge between the paired handle and blade assemblies, in the pivot zone.

pivot zone. It will have been observed that no additional attachment bolts are required incident to the usage of the improved stop and hinge assembly described, inasmuch as the companion hinge sections or fittings are secured in place, substantially in vertical registry, by the same bolts 20 as are utilized for attachment of the blades to the handles.

Although for convenience and brevity of description the improved stop-hinge assembly has been described as designed for and applied to a reciprocating-handle type of post hole digger, the same fittings, with or without minor modification, may be applied to certain other two-handled bladed tools, for example, hedge clippers and other implements which are operated by similar reciprocal movement of the handles in opposite directions.

30 Although the invention has been described by particularized reference to a selected commercial embodiment, the detail of description should be understood solely in an illustrative, rather than in any limiting sense, numerous variants being possible within the fair scope of the claims hereunto appended.

35 I claim as my invention:

1. A combined stop and pivot assembly for a post hole digger having a pair of handles, and a hollow blade carried by the lower end of each handle, the pivot assembly comprised of two companion coating parts, each such part including a base attached to an inside face portion of one handle near its lower end, a pair of apertured pivot ears carried by and projected outwardly of the base toward the opposite handle, the two parts of the pivot assembly being vertically in register, with the pivot ears of one of said parts laterally adjacent corresponding ears of the companion part, and with the apertures of the ears in register, a pivot pin common to and extended through the several ear apertures, and stop arms carried by the respective said parts of the pivot assembly in positions to abut each other above said pivot pin upon extreme approaching movement of the handles, and serving thereby to limit the handle spacing in one position of the relatively movable parts, said stop arms being located at an appreciable distance upwardly of the handles, 5 in respect to the pivot pin.

in respect to the pivot pin.

2. A combined stop and pivot assembly for a hand implement such as a post hole digger having a pair of handles, and a pair of opposed hollow blades, one attached to the lower end of each handle, the pivot assembly comprised of two parts which coact to constitute a hinge between the handled blades, each of the two parts of the pivot assembly including a substantially flat base attached to the inside surface portion of a lower end of one handle, a pair of apertured pivot ears projecting in a direction away from the base and the handle by which it is carried, the pivot ears of one said part overlapping the corresponding ears of the companion part, with the ear apertures in register, a pivot pin extended through the several ear apertures, a stop arm constituted as a right angled, inturned projection of each of the bases of the pivot assembly and arranged to abut each other above said pivot pin when the blades are open, the abutting stop arm portions being provided with cooperating tongues and recesses for mutually interfitting relation when the blades are fully opened, whereby to

keep the handles and blades in parallelism, and to relieve the pivot pin of cocking or twisting tendencies, the said parts of the pivot assembly consisting of elements separate from the blades and handles.

3. A combined stop and hinge assembly for a two-handled, bladed tool in which each handled blade is pivotally related to the other, the assembly consisting of a pair of coacting metal hinge elements each including a base plate, paired, spaced, apertured ears projected marginally from and integral with the base plate, the base plate being apertured for mounting members such as bolts or rivets, and a stop arm on each base plate at a distance from the apertured ears, and a hinge pin extending as a pivot through the several apertures, the stop arms being provided with interfitted portions for interfitting laterally-aligning engagement above said hinge pin when brought together.

4. The combination and arrangement of elements in a combined stop and hinge assembly substantially as recited by claim 3, but further characterized by the provision of an outwardly convergent tongue at the free end of one stop arm and a compatible tongue-receiving recess in the region of the free end of the opposite stop arm, the tongue and recess being proportioned for reception of the tongue in the recess when the stop arms are brought together.

5. As an article of manufacture, a combined stop and hinge assembly for the paired handled blades of a post hole digger, said assembly consisting of two hinge elements, each said hinge element comprising an elongate base plate provided with longitudinally spaced bolt apertures, the base plates being adapted for longitudinal

mounting on the respective inside faces of lower handle portions of the digger, the lower end of each base plate having outturned, apertured pivot ears, one projecting integrally from each side margin of the plate, the apertures of the ears being located appreciably outwardly of the base plate, the end of each base plate opposite the pivot ears being turned outwardly of the base plate at a right angle thereto, whereby to provide a rigid stop arm spaced substantially away from the region of the pivot ears, a bolt extended through the several apertures of the pivot ears to provide a hinge pin between the base plates and parts connected thereto, the free marginal portions of the stop projections of the base plates being provided with a series of deep reentrant portions constituting open recesses, with projecting teeth intervening said recesses, and with the teeth and recesses of the cooperating stop arms adapted for mutual interfitting abutment above said pivot bolt when the stop arms are brought together, the aggregate length of the stop arms being substantially equal to the aggregate distance from the centers of the apertures of the ears, to the respective base plates, whereby in assembly, the stop arms together with the pivot ears and pivot bolt, coact to maintain the handles of a tool in substantial parallelism when the handles are brought to full convergence.
